SAFETY PIN

Henry Clay Whittaker, Memphis, Tenn.

Application August 10, 1950, Serial No. 178,692

1 Claim. (Cl. 24—156)

1

This invention relates to improvements in safety pins.

Due to the fact that the pin of the usual safety pin has a tendency to pull away from the guard when under pressure, it has been proposed to bend the end of the penetrating point at a slight angle and this end is seated within a similarly inclined pocket in the guard, where the point is turned inwardly the tendency to slip has not been removed. Again the point may be bent outwardly and is received by a pocket of the guard which is provided with slots to seat the point. Further, it has been proposed to provide a guard having a shield to receive the point of the pin. However, in all of the proposed structures, the pointed end of the pin is not properly protected from disengagement from the guard when under pressure.

It is an object of the present invention to provide a safety pin in which the penetrating point of the pin is retained in the guard by a plurality of elements combined in the pin and guard in which the free end of the pin has a straight portion and a curved portion nested within similarly positioned channeled portions of an arm of a U-shaped guide, the pointed end of the penetrating pin being restricted in the inward movement by the other arm of the U-shaped guard since the curved portion of the first mentioned arm retains the pointed end in close association with the second arm.

A further object of the invention is the provision of a safety pin in which the legs of a U-shaped member have intermediate portions bowed inwardly towards each other so that when the materials of clothing are forced between the bowed portions an outward pressure will be exerted on the legs to prevent the penetrating pin forming one of the legs from being displaced accidentally from a guard carried by the other leg.

This invention is best understood from a consideration of the following detailed description in conjunction with the accompanying drawing, nevertheless it must be borne in mind that the invention is not confined to the disclosure, but is susceptible to such changes and modifications as shall define no material departure from the salient features of the invention as expressed in the appended claim.

In the drawings:

Figure 1 is a greatly enlarged top plan view of my improved safety pin shown in closed position,

Figure 2 is a similar top plan view of the pin in open position,

Figure 3 is a reduced transverse vertical section of the pin taken along the line 3—3 of Figure 1, and

2

Figure 4 is a greatly enlarged top plan view of a modified form of the pin.

Referring more particularly to the drawing, 10 designates generally a U-shaped member having a bight portion 11 in the shape of a coil. The legs 12 and 13 of the U-shaped member and the coil are formed of spring material such as brass or steel so that the free ends of the legs will tend to spring apart.

10 The leg 12 has an inwardly bowed portion 12a intermediate its length, extending for the major portion of the length thereof. A hook 14 is provided at the outer free end of said leg which is received within a reduced end 15 of a guard 16.

15 The guard is formed with a pair of substantially parallel arms 20 and 21. The arm 21 is U-shaped in cross section as shown more particularly in Figure 3. An inwardly curved portion 22 is included in the arm 21 with the outer end of 20 said portion merging integrally into the reduced end 15 of the guard. The arm 20 is also formed integrally with the reduced end. A pair of ears 23 project inwardly from the inner ends of the side walls of the U-shaped arm 20 and in flat 25 contact with each other to provide a guide for a purpose which will be explained presently. It will be noted that the side walls of the U-shaped arm 20 inwardly of the leg 12 are pressed together so that the arm will form a tight fit around the enclosed portion of the leg 12 and hook 14, as shown at 24 to prevent said arm from 30 being rotated on the leg. A finger 25 extends inwardly from the inner end of each side wall of the arm 21. The fingers are in parallel relation, 35 and are spaced from the juxtaposed ears 23 with said ears being located between the fingers 25.

The leg 13 extends in integral formation from one end of the coil 11 and has a portion 26 seated within that part of the channel member 21 which 40 is parallel to the arm 20 when the leg or pin 13 is in closed position. The free end 27 of the pin has the same curved inclination as the inturned portion 22 of the arm 21 so that the point 28 of the pin will be housed within the portion 22 in such a manner that the point cannot be dislodged from the guard.

In Figure 4, a slightly modified form is shown in which the legs 12b and 13a are bowed inwardly towards each other as shown at 30. However, these inwardly bowed portions are spaced sufficiently apart in order that the leg or pin 13a may be swung inwardly towards the leg 12b to an extent that the members 26, 27 and the point 28 may be removed from the channeled arm 21 of the guard 16. The legs 12b and 13a extend from

the coiled bight 11. In view of the fact that all of the other elements of the pin illustrated in Figure 4 are identical in structure with similarly positioned elements shown in Figure 1, the same reference numerals are employed for such elements. The inwardly bowed portions 30 of the legs, when the pin or leg 13a has been forced through a piece of cloth, are placed under tension for maintaining the point of the pin in the guard. In other words, a sufficient portion of the cloth may be forced between the bowed portions 30 to prevent displacement of the pin or leg 13a from the guard.

In operation, the intermediate portions of legs 12 and 13 (Figures 1 and 2) are pressed towards each other whence the elements 26, 27 and 28 are forced from the arm or channel member 21 of the guard. However, said elements must be moved inwardly towards and beyond the arm 20 so that this part of the leg or pin 13 which is in contact with the fingers 25 will clear the inner free end of one of the fingers before the pin 13 can be released sufficiently for withdrawal from the piece of cloth.

It will be noted that the elements 26, 27 and 28 of the pin 13 are completely housed within the channelled arm 21 including the inclined portion 22 of the guard 16. The point 28 is so confined within the portion 22 of the arm 21 that it cannot be released accidentally from said arm, in view of the fact that said point is restricted in movement by the closely associated inner edge of the arm 20. Such close association does not prevent manual release of the point and elements 26 and 27 when properly guided by the contacting ears 23. Furthermore, the free end of the pin 13 cannot be pulled out of the arm 21 when the safety pin is in use on clothing.

The pin illustrated in Figure 4 presents an additional safety measure against the accidental removal of the pin or leg 13a from the guard 16. When the pin has been forced through clothing, the cloth will be forced between the restricted portions 30 of the legs 12b and 13a thereby exerting a pressure on the leg 13a for maintaining the elements 26, 27 and 28 housed rigidly within the arm 21 including the inclined portion of the guard. The pin or leg 13a can be manipulated

readily by pressing inwardly on said pin and leg 12a at points located between the inbowed portions 30 and the inner end of the guard 16.

I claim:

5 A safety pin comprising a substantially U-shaped guard including a channelled straight arm, a second channelled arm having an inclined curved portion extending outwardly at an acute angle from the outer end of the straight arm and a portion projecting from the inclined portion and parallel to the straight arm, the inclined and parallel portions forming a protective housing, a U-shaped member formed of spring material and having one leg thereof secured in the straight arm, the other leg providing a penetrating pin, the end of the pin having an inward inclined curvature of the same angle as the inclined portion of the second arm of the guard and adapted to be seated in said portion when the pin is closed, a portion of the pin inwardly of the inclined end being seated within the parallel portion of the second channelled arm, the first mentioned leg of the U-shaped member being provided with an inbowed portion intermediate the ends thereof and extending for the major portion of the length of the leg, the inbowed portion restricting the space between the major portion of the length of both legs so that when the safety pin is applied to a piece of clothing, the cloth between the inbent portion and the pin leg will exert an outward pressure on the leg of the penetrating pin.
